UNITED STATES PATENT OFFICE.

JOHN McD. HARPER, OF COLFAX, WASHINGTON TERRITORY.

CAR-COUPING.

SPECIFICATION forming part of Letters Patent No. 292,910, dated February 5, 1884.

Application filed November 8, 1883. (No model.)

To all whom it may concern:

Be it known that I, JOHN McD. HARPER, a citizen of the United States, residing at Colfax, in the county of Whitman and Territory of Washington, have invented a new and useful 5 Car-Coupling, of which the following is a specification, reference being had to the accompanying drawings.

My invention relates to car-couplings, the object being to provide a device of this character of cheap, simple, and durable construction, and one that shall be thoroughly effective in its operation.

The invention consists in the improved construction and combinations of parts, hereinafter fully described, and pointed out in the claims.

In the drawings, Figure 1 is a longitudinal vertical section of my improved coupler applied to a car. Fig. 2 is a side elevation of the same, and Fig. 3 is a transverse vertical section on the line $x-x$ of Fig. 2. Fig. 4 is a bottom view.

A represents the platform of the car, to the under side of which is secured a block or bar, B. To the under side of this block or bar B is attached the draw-bar C, the front end of which projects beyond the end of the block, and is provided with a dovetailed flange, g^3 , for a purpose to be more fully described.

D represents the draw-head, the rear end of which is provided with a dovetailed groove, f^4 , to receive the dovetailed flange f^3 of the bar C. A lever, E, is pivoted to the under side of the block B. One end of said lever is secured to the under side of the draw-head. Thus the draw-head is rendered vertically adjustable to adapt itself to any height of car.

F represents a latch, the forward end of which is pivotally secured to the front end of the draw-head D. The rear end of this latch F is provided with a longitudinal slot, F', to fit over the coupling-hook.

H' represents a spring secured one end to the upper inner side of the draw-head and the other end to the latch F.

G represent blocks or strips secured to the inner sides of the draw-head, their upper faces being inclined toward the rear end of the draw-head, the same limiting the downward move-

ment of the latch further to insure perfect coupling. The under side of the draw-head is provided with a longitudinal slot, H, extending nearly its entire length. In the front end of this slot H is pivoted the front end of the coupling-hook I, the rear end of which is cut away and forms an angular coupling portion, a.

To the rear end of the coupling-hook I is secured a coil-spring, b. To the end of this spring b is secured a chain, b³, which passes 60 through a groove, c, formed in the rear end of the draw-head, and from thence over a pulley, d, mounted on the under side of the car, which is grooved or channeled to receive it.

The forward end of the platform is provided 65 with an opening, e³, to receive a shaft, e, having at its upper end a hand-wheel, e⁴, and provided at its lower end with a drum, to which the chain is secured, and upon which it is adapted to be wound.

One side of the draw-head is provided with a vertical slot or opening, f, through which projects an angular rod, g, carrying at its end a head or clapper, g', which strikes an alarm, g³, secured to the under side of the draw-head, 75 when the coupling has been effected.

To the under side of the draw-head D is secured a U-shaped bracket, G², which limits the downward movement of the coupling-hook when the same is disengaged from the link to 80 uncouple the cars.

The operation is as follows: The coupling-link of the adjacent car strikes against the forward end of the coupling-hook, and as the same is inclined upwardly the link strikes the 85 rear end of the latch, raising the same and allowing the link to drop over the end of the coupling-hook. The latch then descends and strikes the alarm, as described, to show that the cars have been coupled. When the cars 90 are to be uncoupled, the shaft e is turned or reversed, loosening the chain, thus allowing the coupling-hook to drop by means of gravity, the bracket on the under side of the draw-head limiting its downward movement further than 95 to allow of the coupling-link being withdrawn.

Having fully described my invention, what I claim as new, and desire to secure by Letters Patent, is—

1. In a car-coupling, the combination, with 100

the car or platform having a block secured to its under side, the front end of which is provided with a dovetailed flange, of a draw-head having a corresponding dovetailed groove to receive the dovetailed flange of said block, and a lever pivoted to the under side of the said block, its end being secured to the under side of the draw-head, whereby the said draw-head is rendered vertically adjustable, substantially as set forth.

2. The combination, with the draw-head slotted on its under side, of a coupling-hook pivotally secured in the forward end of said slot, a coiled spring secured to the rear end of said hook, a chain secured to said spring, a pulley journaled to the under side of the car, and a shaft having a drum and hand-wheel and mounted in the forward end of the platform, said chain being secured to said drum and adapted to be wound thereon, substantially as set forth.

3. The combination, with the draw-head having blocks or strips secured on its inner sides, of a latch pivoted in the forward end of said draw-head and slotted at its rear end, and a coupling-hook pivoted in a slot in the draw-head, substantially as set forth.

4. The combination, with the draw-head having blocks or strips secured on its sides, of a latch pivoted in the forward end of said draw-head and slotted at its rear end, an angular rod secured to the side of said latch, and extending through an opening in the side of the draw-head, an alarm secured to the under side of the draw-head, and a coupling-latch, substantially as set forth.

5. The combination, with the draw-head slotted on its under side, of a coupling-latch pivoted in the forward end of said draw-head, and having a spring secured to its rear end, a chain connecting said spring and the shaft *e*, and a U-shaped bracket secured to the under side of the draw-head to limit the downward movement of the coupling-hook, substantially as set forth.

In testimony that I claim the foregoing as my own I have hereto affixed my signature in presence of two witnesses.

JOHN McD. HARPER.
